UNITED STATES PATENT OFFICE.

MAURICE LINFOOT, OF BOCKING, BRAINTREE, ENGLAND, ASSIGNOR TO COURTAULDS LIMITED, OF LONDON, ENGLAND.

PROCESS OF ORNAMENTING FABRICS.

1,137,501.

Specification of Letters Patent. Patented Apr. 27, 1915.

No Drawing.

Application filed February 3, 1914. Serial No. 816,140.

To all whom it may concern:

Be it known that I, MAURICE LINFOOT, a subject of the King of Great Britain, residing at The Knoll, Bocking, Braintree, in the county of Essex, England, have invented new and useful Improvements in a Process of Ornamenting Fabrics, of which the following is a specification.

This invention relates to improvements in applying various effects, patterns, or designs, to fabrics by superposing, as hitherto, two fabrics and subjecting the superposed fabrics to the action of steam and the said invention has for its object to so improve this method that the said fabric may be figured, or provided with a pattern or patterns of any kind to suit the desired requirements, for example there may be imparted to the said finished fabric the effect of a plain, or other weave, or a striped or figured effect, or a crêpe effect.

According to this invention I employ a fabric possessing the desired weave, effect, pattern, or design, for example, a cotton crêpe fabric, which I will call the pattern fabric, and this is applied to the fabric to be treated by pressure while steam is passed through the superposed fabrics, the fabric to be treated being protected by a thick 20 felted cotton cloth, or its equivalent, which acts as a bed, or apron, for the fabric under treatment, and prevents both sides of the fabric being ornamented. For example I may use a perforated roll on which the fabrics together with a suitable fabric constituting a backing are wound face to face, the fabric under treatment being innermost then the pattern-fabric, and lastly the backing material and through the fabrics so superposed and while under pressure steam is passed at a suitable pressure. In superposing the fabrics it is essential that the backing material be so placed with respect to the fabric under treatment that, when the transference of the ornament is being effected, the backing material is in contact with that face of the fabric on which the ornament is not required. This is obviously the case in the arrangement described, since a large 40 number of windings are made on the roll at each treatment. The backing cloth of the innermost winding obviously lies adjacent the back of the superposed winding of the fabric under treatment, the finish face of which is 55 juxtaposed to the face of the pattern fabric,

while outside the latter lies the backing fabric. The steam may be subsequently exhausted from the fabrics and cold or heated air drawn through the same to dry the said fabrics, or any other suitable apparatus for applying the pattern, or design, of the pattern-fabric to the fabric under treatment may be used which comprises the use of steam and pressure.

The process is especially adapted for treating fabrics of artificial silk, a remarkable effect of an increased lustrous sheen being imparted thereto, which considerably increases the rich effect of the said fabrics, it also produces a softer handle or finish than can be otherwise obtained, while irregularities in the structure of the fabric are effaced.

What I claim is:—

1. A process of ornamenting textile fabrics which consists in forming a layer comprising a fabric to be treated, a pattern fabric and a permeable bed or apron, said fabrics being superposed in the order named and the finish face of the fabric to be treated being juxtaposed to the face of the pattern fabric, subjecting the ensemble to pressure and causing a heated fluid to pass therethrough.

2. The process of ornamenting textile fabrics which consists in forming a plurality of superposed layers comprising in each layer, a fabric to be treated, a pattern fabric and a permeable bed or apron, said fabrics being superposed in the order named and the finish face of the fabric being juxtaposed to the face of the pattern fabric, subjecting the ensemble to pressure and causing a heated fluid to pass therethrough.

3. A process of ornamenting textile fabrics which consists in forming a layer comprising a fabric to be treated, a pattern fabric and a permeable bed or apron, said fabrics being superposed in the order named and the finish face of the fabric to be treated being juxtaposed to the face of the pattern fabric, subjecting the ensemble to pressure and causing steam to pass therethrough.

4. A process of ornamenting textile fabrics which consists in forming a layer comprising a fabric to be treated, a pattern fabric and a permeable bed or apron, said fabrics being superposed in the order named and the finish face of the fabric to be treated being juxtaposed to the face of the pattern fabric, subjecting the ensemble to pressure

and causing steam to pass therethrough, and subsequently exhausting the steam from the fabrics.

5. A process of ornamenting textile fabrics which consists in forming a layer comprising a fabric to be treated, a pattern fabric and a permeable bed or apron, said fabrics being superposed in the order named and the finish face of the fabric to be treated being juxtaposed to the face of the pattern fabric, subjecting the ensemble to pressure and causing steam to pass therethrough, subsequently exhausting the steam from the fabrics and thereafter drying the fabrics.

15. 6. A process of ornamenting fabrics which consists in winding on a roll, a fabric to be ornamented, a pattern fabric and a plain backing cloth, the said fabrics being superposed in the order named, the face of the pattern fabric lying against the finish face of the fabric to be ornamented and subjecting the said fabrics so superposed to pressure and causing steam to pass therethrough.

25. 7. A process of ornamenting fabrics which consists in winding on a roll a fabric to be ornamented, a pattern fabric and a relatively heavy plain backing cloth which forms a bed or apron for the fabric to be ornamented, the said fabrics being superposed in the order named, the face of the pattern fabric lying against the finish face of the fabric to be ornamented and subjecting the said fabrics so superposed to pressure and causing steam to pass therethrough.

35. 8. A process of ornamenting fabrics which consists in winding on a roll, a fabric to be ornamented, a pattern fabric and a plain backing cloth, the said fabrics being superposed in the order named, the face of the pattern fabric lying against the finish face of the fabric to be ornamented and subjecting the said fabrics so superposed to pressure and causing steam to pass therethrough.

45. pressure and steam, thereafter exhausting the steam from the fabrics and passing a drying medium therethrough.

9. A process of ornamenting fabrics which consists in winding on a perforated roll, a fabric to be ornamented, a pattern fabric and a plain backing cloth, said fabrics being juxtaposed in the order named and the face of the pattern fabric lying against the finish face of the fabric to be ornamented, subjecting said fabrics so superposed to pressure and causing steam to pass therethrough.

10. A process of ornamenting fabrics which consists in winding on a perforated roll a fabric to be ornamented, a pattern fabric and a relatively heavy plain backing cloth which forms a bed or apron for the fabric to be ornamented, said fabrics being juxtaposed in the order named and the face of the pattern fabric lying against the finish face of the fabric to be ornamented, subjecting said fabrics so superposed to pressure and causing steam to pass therethrough.

11. A process of ornamenting fabrics which consists in winding on a perforated roll, a fabric to be ornamented, a pattern fabric and a plain backing cloth, said fabrics being juxtaposed in the order named and the face of the pattern fabric lying against the finish face of the fabric to be ornamented, subjecting said fabrics so superposed to pressure and steam, thereafter exhausting the steam from the fabrics and passing a drying medium therethrough.

In testimony whereof I have signed my name to this specification in the presence of two subscribing witnesses.

MAURICE LINFOOT.
